[57] ABSTRACT

An integrated voltage-stabilizing network with grounded substrate has an input terminal, an output terminal and a reference terminal, the latter being held at a fixed potential relative to the output terminal by a regulator also delivering a constant current to that reference terminal which is connected to a tap on a voltage divider inserted between the output terminal and ground. The regulator is connected in the base/emitter circuits of two parallel transistors which lie between the input and output terminals and deliver respective components of an output current, one of these parallel transistors lying in series with a further transistor which is paired with a similar transistor supplying a like current components to the reference terminal.

FIG. 2

INTEGRATED VOLTAGE STABILIZER WITH NEGATIVE INTERNAL RESISTANCE

My present invention relates to a voltage stabilizer, particularly one of the integrated type, in which an internal negative resistance compensates for changes in the output voltage due to variations in load current.

Such voltage stabilizers are useful for the energization of low-power d-c motors employed, for example, to drive record players, tape or cassette recorders and similar devices in which the load changes but little during normal use and which can be operated by low-voltage batteries of, say, 6 V or less.

The general object of my present invention is to provide a system of this character which is of simple construction and lends itself to inexpensive mass production.

A more particular object is to provide an integrated-circuit module of this description having but three live terminals (referred to hereinafter as input terminal, output terminal and reference terminal) to be connected between the current source and the load, thereby minimizing the number of external impedance elements required.

A voltage stabilizer according to my invention comprises, essentially, a constant-voltage generator connected between the output and reference terminals, the latter terminal being tied to a tap on a voltage divider inserted between the output terminal and ground. The reference terminal also receives a current component, proportional to the current emitted by the output terminal, from a current-sensing circuit which is connected between the input terminal on the one hand and the output and reference terminals on the other hand. As will be shown hereinafter, this arrangement establishes a negative resistance of a magnitude proportional to the load current.

In the preferred embodiment described hereinafter, the constant-voltage generator supplies to the reference terminal a substantially constant reference current which supplements the proportional current component delivered by the sensing circuit. The latter advantageously includes two main transistors connected in parallel branches between the input and output terminals for respectively controlling the magnitude of a first and a second component of the load current, the two transistors being so interconnected that these current components are identical or otherwise maintain a predetermined ratio. A further transistor, in series with one of the two main transistors, is paired with an image transistor with draws a matching current and supplies it to the reference terminal as the current component proportional to the output current. The constant-voltage generator is common to the base/emitter circuits of the two main transistors.

All the components referred to, with the possible exception of the voltage divider, may be incorporated in an integrated circuit whose substrate (e.g. a silicon wafer) may be grounded.

The above and other features of my invention will now be described in detail with reference to the enclosed drawing in which:

FIG. 1 is a circuit diagram showing a voltage stabilizer embodying the present invention; and

FIG. 2 is a more detailed diagram of a component of the stabilizer shown in block form in FIG. 1.

The voltage stabilizer depicted in FIG. 1 comprises an integrated-circuit network CI with grounded substrate including a control circuit A and a current-sensing circuit B. A supply voltage V_{in} from a nonillustrated source of direct current is applied between ground and an input terminal 1; a load, shown as a d-c motor M, is energized by a current I_{out} at a voltage V_{out} on being connected between ground and an output terminal 2. A reference terminal 3 is tied to a tap of a voltage divider inserted between output terminal 2 and ground, this voltage divider consisting of a resistor R_a in series with a preferably adjustable resistor R_b .

Terminals 1 and 2 are interconnected by two circuit branches 4, 5 including respective main NPN transistors T_0 and T_1 along with associated emitter resistors R_1 and R_2 . Transistor T_0 , though shown included in the control circuit A, may also be considered part of sensing circuit B along with its physically identical mate T_1 . The sensing circuit includes a further transistor T_2 with emitter resistor R_3 , in series with transistor T_1 , and an image transistor T_3 lying with its emitter resistor R_4 in the current path 6 between terminals 1 and 3; transistors T_2 and T_3 are of PNP type. The two identical transistors T_2 and T_3 have their bases connected to the collector of transistor T_1 so as to be traversed by identical currents I_1' and I_1'' whose magnitude bears a predetermined relationship with that of the output current I_2 issuing from terminal 2. This output current splits into the actual load current I_{out} and a branch current I_2' traversing voltage divider R_a , R_b .

A constant-voltage generator CV, more fully described below with reference to FIG. 2, has two output leads 7, 8 respectively connected to terminals 2 and 3. Generator CV develops a substantially invariable voltage V_0 across these two leads and energizes lead 8 with a substantially constant current I_0 . Thus, the current I_3 issuing from terminal 3 represents the sum of currents I_0 and I_1'' .

Since $I_2' = V_0/R_b$, we can write

$$V_{out} = V_0 + R_a (I_3 + V_0/R_b)$$

Also, with $I_1'' = KI_2$ (K being a constant) in view of the pairing of transistors T_0 , T_1 , on the one hand, and T_2 , T_3 , on the other hand,

$$I_3 = I_0 + I_1'' = I_0 + KV_0/R_b + KI_{out}$$

50

From equations (1) and (2) we obtain the following value for the load voltage V_{out} :

$$V_{out} = V_0 [1 + R_a/R_b (1 + K) + R_a I_0 + K R_a I_{out}]$$

55

Under the assumed conditions, the first two terms of equation (3) are independent of input voltage V_{in} and load current I_{out} , the amplitude of this constant voltage component being adjustable with the aid of resistor R_b .

The third term $K R_a I_{out}$ of equation (3) is a voltage component proportional to load and is the equivalent of the voltage drop generated by current I_{out} across a negative resistance of amplitude $K R_a$. The value of $K R_a$ should be less than or at most equal to the effective load resistance R_L in order to avoid instability. Since the constant K is independent of the setting of resistor

R_b , adjustment of the latter varies the load voltage V_{out} without affecting the negative resistance.

As illustrated in FIG. 2, constant-voltage generator CV comprises a number of transistors $T_4 - T_{12}$ and associated resistors $R_5 - R_{13}$. Transistors T_4 and T_5, T_7 and T_8 as well as T_9 and T_{11} represent successive 2-transistor amplifier stages generating a modified replica of voltage V_0 which is to be held constant, this voltage being fed back from lead 7 to the base of transistor T_6 in series with transistor T_4 and to the base of the latter 10 transistor by way of resistor R_6 . The two transistors of each amplifier stage are connected in cascade, with the emitter of one transistor tied directly to the base of the other transistor. Transistors $T_4 - T_7$, whose base/emitter resistances are of large value compared with resistor 15 R_5 , form part of a temperature-compensating chain which neutralizes the effect of temperature variations upon the base/emitter resistances of the circuit as far as their effect upon the input voltage of amplifier stage 20 $T_9 - T_{11}$ is concerned. For a detailed mathematical analysis, reference is made to my copending application Ser. No. 283,421 filed on even date herewith.

The output voltage of transistor T_8 is developed across resistor R_8 which is also connected to lead 7 so as to carry the voltage V_0 . Transistor T_{10} , connected as a diode, is inserted between ground and the emitter of transistor T_9 in series with resistor R_{12} whose magnitude may therefore be reduced.

The collector of final transistor T_{11} is connected to the base of transistor T_{12} and through resistor R_{13} to the emitter thereof which in turn is tied to a conductor 9 interconnecting the bases of transistors T_0 and T_1 (the latter not having been illustrated in FIG. 2); resistor R_{10} lies between conductors 4 and 9 so that the series combination of this resistor and transistor T_{12} shunts the 35 transistor T_0 and its emitter resistor R_1 . Any change in the voltage V_0 is communicated by way of the feedback loop including transistors $T_4 - T_{11}$ to the base of transistor T_{12} which is of PNP type, in contradistinction to all the other transistors shown in FIG. 2; the polarity of the 40 control voltage delivered by this feedback loop to the base of transistor T_{12} is such that the base/emitter voltage of transistor T_0 varies in a sense minimizing the change in voltage V_0 . Thus, at least in first approximation, voltage V_0 can be considered constant along with the current I_0 traversing the transistor T_{11} .

It will be seen that the system according to my invention does not require the use of a constant-voltage and/or constant-current source extraneous to the inte-

grated network CI.

Emitter resistors R_1, R_2 and R_3, R_4 are not essential but serve to reduce the effect of any residual disparity between the paired transistors T_0, T_1 or T_2, T_3 .

I claim:

1. A voltage stabilizer comprising: an input terminal, an output terminal and a reference terminal, said input terminal being energizable by a grounded source of direct current, said output terminal being connectable to a grounded load; a voltage divider inserted between said output terminal and ground, said reference terminal being tied to a tap on said voltage divider; a generator of constant voltage connected between said output and reference terminals; and current-sensing means connected between said input terminal on the one hand and said output and reference terminals on the other hand for supplying to said reference terminal a current component proportional to an output current issuing from said output terminal.

2. A voltage stabilizer as defined in claim 1 wherein said generator and said current-sensing means are part of an integrated network.

3. A voltage stabilizer as defined in claim 2 wherein said integrated network is carried on a grounded substrate.

4. A voltage stabilizer as defined in claim 1 wherein said current-sensing means includes a first and a second transistor connected in two parallel branches between said input and output terminals for respectively delivering a first and a second component of the output current bearing a predetermined relationship, and a matching circuit in the second of said branches for supplying said proportional current component as the image of said second component.

5. A voltage stabilizer as defined in claim 4 wherein said matching circuit includes a further transistor in series with said second transistor and an image transistor connected in parallel with said further transistor.

6. A voltage stabilizer as defined in claim 4 wherein each of said first and second transistors has a base/emitter circuit connected across said generator.

7. A voltage stabilizer as defined in claim 1 wherein said generator includes circuitry for delivering a substantially constant reference current to said reference terminal.
